Mich.

Application April 2, 1934, Serial No. 718,576

8 Claims. (Cl. 261—34)

This invention relates to fuel feeding devices for internal combustion engines.

More particularly the invention provides improved apparatus commonly called pick-up pump mechanism for temporarily augmenting the supply of fuel to an internal combustion engine during accelerating the speed of operation thereof. One of the main objects of the invention is to provide improved apparatus of this character which is adapted to promptly supply an initial augmenting charge of fuel to the fuel system of an internal combustion engine during opening of the valve thereof, and to subsequently supply delayed augmenting charges thereto at different rates of discharge during a limited period following cessation of the opening movement of the throttle valve.

Other objects of the invention are to provide a primary fuel displacing member in apparatus of this character which is adapted to discharge fuel both during and after throttle opening movements; to provide a secondary fuel displacing means which is adapted to discharge fuel at a different rate than said primary fuel displacing means after operation of the latter is discontinued; to provide a secondary fuel displacing means of this kind which is adapted to operate a valve for controlling the flow of fuel from a pick-up pump mechanism; and to provide fuel displacing members, one adapted to displace a delayed discharge of fuel immediately after opening movement of the throttle is discontinued and the other being adapted to displace a further delayed discharge of fuel at a lower rate after the first mentioned displacing means is inoperative.

Other objects of the invention are to provide means in apparatus of this character for delivering the augmenting fuel charges to the fuel mixture intake passage of a fuel system independently of the normal liquid fuel feeding means; to provide means for preventing a flow of fuel from the charge augmenting apparatus when the latter is not operating; to provide valve mechanism for this purpose which is adapted to be opened by the pressure applied on the fuel charge during initial movement of the throttle valve toward an open position; to provide means in valve mechanism of this character which is adapted to prolong the delayed discharge until the augmenting charge valve is completely closed; and to provide operating mechanism for a valve of this kind which is adapted to limit and relieve the pressure created during rapid throttle opening movements.

Further objects of the invention are to provide means in a pick-up pump mechanism for limiting opening of the augmenting charge valve when the throttle valve is opened rapidly so as to prevent overloading of the carburetor with fuel and to preserve some of the fuel for the delayed discharges; and to provide means and apparatus of this kind for decreasing the discharge of fuel when the carburetor throttle in conjunction with which it operates is opened to a desired extent.

Illustrative embodiments of the invention are shown in the accompanying drawings, in which:

Fig. 1 is a side elevational view of a carburetor partly in vertical section showing our improved pick-up pump.

Fig. 2 is a fragmentary vertical sectional view taken on the line II—II of Fig. 1.

Fig. 3 is a vertical sectional view taken on the line III—III of Fig. 2.

Fig. 4 is a vertical sectional view taken on the line IV—IV of Fig. 1.

Fig. 5 is a fragmentary sectional view of a carburetor showing a pick-up pump that embodies a modified form of the invention, in an inoperative condition.

Fig. 6 is a view similar to Fig. 5 showing a pick-up pump mechanism in an operative position.

Fig. 7 is an enlarged, fragmentary sectional view of the pistons embodied in the form of the invention illustrated in Figs. 1 to 4, inclusive, showing the latter in changed position.

In the form shown, a carburetor in which our improved pick-up mechanism is illustrated is of the down-draft type. The pick-up mechanism may, however, be incorporated in an up-draft carburetor with equal facility. The down-draft carburetor disclosed for the purpose of illustration includes a body portion 10 in which is formed a fuel mixture passage 11 having an air inlet 12 and an outlet 13 for delivering fuel mixture to an intake manifold of an engine (not shown). The body portion 10 of the carburetor is provided with a fuel reservoir 14 having an inlet 15 which is controlled by a valve 16. The valve 16 is operated by conventional float mechanism 17 which predetermines the fuel level in the reservoir.

Formed on one side of the carburetor is a pick-up pump cylinder 18 having a cylindrical bore 19 in which a hollow piston 20 is slidably mounted. The outer periphery of the piston 20 fits tightly against the inner peripheral wall of the bore 19 of the cylinder and it is provided with a central, axially extending passage 21 in which a second hollow piston 22 is slidably mounted. The piston 20 has a spider 23 extending across

the upper end of the passage 21 in which a rod 24 of the pump actuating mechanism is slidably mounted.

The pump actuating mechanism includes a lever arm 25 non-rotatably fixed to one end of a rotatable throttle valve shaft 26 having a throttle valve 27 thereon disposed in the outlet end portion 13 of the fuel mixture passage 11. The rod 24 is operatively connected with the lever arm 25 by an L-shaped bar 28 slidably mounted in a passage 29 in the body portion 10 of the carburetor and a connecting link 30 pivotally attached to the lower end of the bar 28 and to the lever arm 25. Concentrically mounted on the rod 24 is a coil spring 24' which bears between the upper end portion of the shiftable bar 28 and the spider 23 of the piston 20 in such a manner as to yieldably urge the piston downwardly as viewed in Figs. 1 and 2 when the throttle valve 21 is opened by conventional throttle valve operating apparatus generally designated by the numeral 21'.

The pump cylinder 18 is provided with a fuel inlet 31 communicating at one end with the interior of the fuel reservoir 14 and having an outlet 32 communicating with the interior of the pump cylinder. The outlet 32 is normally closed by a ball valve 33 adapted to open during the suction stroke of the piston 20 to admit fuel to the interior of the cylinder. Formed in the bottom wall of the cylinder 18 is a threaded aperture 34 in which a plug 35 is mounted. The plug 35 has a central passage 36 communicating with a passage 37 extending along the side wall 35 of the cylinder 18 and leading to an inlet port 38 which is preferably provided at the section of maximum constriction with a venturi 39 formed in the fuel mixture passage 11. A threaded metering plug 40 is disposed in the outlet 38 to regulate the quantity of fuel discharged from the pick-up mechanism.

Slidably mounted in an aperture in the lower end of the inner and smaller piston 22 is a valve stem 41 which is adapted to normally close the passage 36 constituting the outlet of the cylinder 18 both during the suction stroke of the piston 20 and while the fuel displacing members thereof are inoperative. The valve stem 41 has a head disposed in the interior of the hollow piston 50 22 engageable by a set screw 42 which is threaded in the lower end of the latter piston. The set screw 42 may be adjusted axially of the hollow piston 22 for the purpose of varying the distances between the lower end of the rod 24 and the upper end of the set screw 42 so as to limit the lift of the piston 22 for wide open pick-up and predetermine the back-lash of the valve stem 41.

In the form of the invention shown in Figs. 60 5 and 6, the general construction of the pick-up 55 pump mechanism is substantially the same as that shown in Figs. 1 to 4, inclusive, and identical parts of the structure are designated by the same numerals employed in the description 65 of the latter figures.

In this form of our invention a piston 43 is 70 slidably mounted in the cylinder 18 and operatively connected with throttle valve control apparatus by a rod 24, spring 24' and L-shaped shiftable bar 28. The rod 24 is fixed to the upper end of the piston 43 and slidably mounted in an aperture formed in the bar 28. The piston 43 has an axially extending passage extending from its lower extremity to an upper end wall 44 having an aperture 45 in which the rod 24 is slid-

ably received. Formed in the side wall of an upper circumferentially relieved portion of the piston 43 are openings 46 which communicate with the axially extending passage thereof. Slidably mounted in the axially extending passage of the piston 43 is a second hollow piston 47 having a lower end wall 48 provided with fuel passages 49 leading to the interior thereof and having a valve stem 41 for closing the outlet passage 38 of the cylinder. The upper end of the piston 47 is closed by a cap 50 and the side wall portions adjacent its upper end are provided with ports 51 which are adapted to register with the openings 46 in the side wall of the piston 43 when the piston 47 is in its retracted position so as to permit by-passing of fuel from the pressure end of the piston 43 to the opposite end thereof through the passages 49, interior of the piston 47, and openings 51 and 46 of the inner and outer pistons, respectively, as illustrated in Fig. 20 6 of the drawings. A spring 55 bearing between the upper end of the piston 43 and the end wall 44 of the piston 47, normally urges the latter outwardly from the piston 43.

In operation of the pick-up mechanism illustrated in Figs. 1 to 4, inclusive, the space at the lower end portion of the cylinder 18 is normally maintained filled with fuel supplied through the passage 31 and inlet 32 during upward movement of the piston 20 accompanying throttle valve closing operations. This fuel is prevented from escaping from the lower end portion of the cylinder 18 by the valve 41. During initial throttle valve opening movements the shiftable L-shaped bar 28 is urged downwardly thereby subjecting the spring 24' to compression and in turn urging the piston 20 downwardly. The downward movement of the piston is opposed by fluid contained in the lower end of the cylinder 18 which acts upon the inner piston 22 causing it to be forced upwardly into the interior of the piston 20 thereby lifting the valve stem 41 from its seat and permitting displacement of fuel from the cylinder to the fuel mixture passage of the carburetor. During moderately rapid opening movements of the throttle valve the resistance to downward movement of the piston 20 offered by the fuel in the cylinder causes the downward movement of the bar 24 to exceed the downward movement of the piston and the spring 24' is placed under compression.

When opening movement of the throttle is discontinued, the spring expands and urges the piston 20 downwardly until the spider 23 engages the head formed on the lower end of the rod 24, thereby providing a delayed discharge of fuel throughout a limited period after operation of the pump actuating mechanism and throttle control apparatus has discontinued. When the piston 30 ceases to apply pressure on the fuel in the lower end portion of the cylinder 18, the inner piston 22 moves downwardly under the action of gravity thereon until the valve stem 41 engages the plug 35 and closes the outer passage extending therethrough. During this downward movement of the inner piston 22 relative to the outer piston 20, a further displacement of fuel is effected and a second delayed discharge of fuel is provided at a different rate than the delayed discharge produced by the piston 20. During excessively rapid throttle valve opening movements, the lower end of the rod 24 of the pump actuating apparatus engages the upper end of the set screw 42 and thereby limits opening of valve 41 sufficiently to prevent an excessive 75

initial discharge of fuel. In this manner opening of the throttle to bring about acceleration of an internal combustion engine is accompanied by a temporary initial augmenting charge and by two stages of delayed augmenting discharges of fuel which may be so controlled as to prevent overloading and to also insure the supply of sufficient fuel during that critical stage of internal combustion engine operation immediately following opening of the throttle valve of the carburetor thereof.

The modified form of our improved pick-up pump mechanism illustrated in Figs. 5 and 6 operates in many respects substantially the same as the pick-up pump mechanism shown in Figs. 1 to 4, inclusive. The initial downward movement of the outer piston 43 accompanying initial throttle valve opening movement raises the inner piston 47 sufficiently to open the valve 41. The spring 24' is placed under compression during the valve opening movement and expands thereafter effecting a delayed discharge of fuel by the piston 43 and the piston 47 descends from its retracted position under the action of gravity producing a further delayed discharge of fuel after movement of piston 43 ceases. In the event, however, of an excessively rapid opening movement of the throttle valve, the inner piston 47 is retracted to the position shown in Fig. 6 and the ports 51 thereof register with the openings 46 of the outer piston 43 and permit bypassing of fuel from the pressure end of the fuel displacing means to the opposite end thereof, in this way decreasing the pressure and the discharge of fuel so as to guard against overloading of the carburetor and fuel system of the internal combustion engine with which it is associated.

Although but several specific embodiments of the invention are herein shown and described, it will be understood that various changes in the size, shape, and arrangement of parts may be made without departing from the spirit of our invention, and it is not our intention to limit its scope other than by the terms of the appended claims.

We claim:

1. In a carburetor, pick-up pump mechanism including a fuel chamber having an outlet for supplying fuel to an internal combustion engine fuel mixture passage, a fuel displacing member in said chamber, means for normally closing said outlet including a valve and an element responsive to the pressure applied on the fuel of said chamber by said fuel displacing member for holding said valve in open position, and apparatus for operating said fuel displacing member having a resilient element constructed and arranged to continue the fuel discharging operation thereof after actuation of said operating apparatus is discontinued and including an element movable relative to said fuel displacing member constructed and arranged to limit the opening of said valve when said operating apparatus is actuated rapidly.

2. In a carburetor, pick-up pump mechanism including a fuel chamber having an outlet for supplying fuel to an internal combustion engine fuel mixture passage, a fuel displacing member in said chamber, means for normally closing said outlet including a valve, apparatus for operating said fuel displacing member having a resilient element constructed and arranged to continue the fuel discharging operation thereof after actuation of said operating apparatus is discontinued

and including an element movable relative to said fluid displacing member constructed and arranged to limit the opening of said valve when said operating apparatus is actuated rapidly.

3. In a carburetor having a fuel mixture passage, a throttle valve for controlling the flow of fuel mixture from said passage, apparatus for regulating said throttle valve, a pick-up pump mechanism including a fuel chamber having an outlet communicating with said fuel mixture passage, a fuel displacing member in said chamber, means operable by said throttle control apparatus for actuating said member during throttle opening movements, and including a resilient element for continuing operation of said member for a limited period after said opening movement of said throttle is discontinued, a member for normally closing said outlet including a valve adapted to be opened by the pressure of the fuel in said chamber, said means having an element engageable with said valve for limiting opening movement thereof when said throttle is widely opened.

4. A pick-up pump including a pump cylinder having a fuel inlet and outlet, telescoping pistons in said cylinder for displacing fuel therefrom, means for actuating the outer piston, the inner piston being energizable by the pressure of the fluid in said cylinder and having a passage therethrough communicating at its ends with the spaces in said cylinder on respectively opposite ends of said outer piston for bypassing fuel from the pressure end to the opposite end of said cylinder during rapid operation of said actuating means.

5. A pick-up pump including a cylinder having a fuel inlet and an outlet, a hollow piston in said cylinder for displacing fuel therefrom, a second piston slidably mounted in said first piston having by-pass orifices in its respectively opposite ends, the by-pass orifice of one end of said second piston being formed in the side wall thereof and adapted to be closed by the wall of said first mentioned piston when said second piston is in an extended position, said second piston being movable to a retracted position by a predetermined pressure of the fuel in said cylinder so as to bypass fuel from one end to the other end of said pistons for controlling the fluid pressure in said cylinder.

6. A pick-up pump including a cylinder having a fuel inlet and an outlet, a piston slidably mounted in said cylinder for displacing fuel therefrom and having a passage therethrough, means for operating said piston, a valve element slidably mounted in said passage for normally closing said outlet, said valve element being movable to a retracted position by the pressure of the fuel in said cylinder and being provided with a passage for bypassing fuel from the pressure end of said cylinder to the opposite end thereof, one end of said by-pass passage being closed by the wall of the passage in said piston when the pressure in said cylinder is below a predetermined value.

7. Pick-up pump mechanism including a pump cylinder having an outlet, an outer hollow piston slidably mounted in said cylinder having its open end facing said outlet and having wall edge portions for displacing fluid from said cylinder, the interior of said outer piston being vented, an inner piston slidably mounted in said outer piston and having a head portion facing said outlet for discharging fuel from said cylinder, a valve carried by said inner piston for controlling said

5

35

50

55

65

5 outlet, said valve and inner piston being operable by the pressure applied on the fuel in said cylinder by said outer piston, and actuating apparatus including a resilient member for operating said outer piston and adapted to predetermine the pump pressure independently of the action of said valve.

10 8. Pick-up pump mechanism including a pump cylinder having an outlet passage, an outer hollow piston slidably mounted in said cylinder having its open end facing said outlet and having wall edge portions for displacing fluid from said cylinder, the interior of said outer piston being

vented directly to the low pressure end of said cylinder, an inner piston slidably mounted in said outer piston and having a head portion facing said outlet passage for discharging fuel from said cylinder, a valve carried by said inner piston normally closing the internal end of said outlet passage and constructed and arranged to open the latter in response to movement of said inner piston away from said outlet, said inner piston being movable away from said outlet by 10 the pressure applied on the fuel.
